ROLLER RAIL FOR INDUSTRIAL HEATING
FURNACES

Henry H. Harris, Champaign, Ill.

Application December 1, 1937, Serial No. 177,428
Renewed July 13, 1939

2 Claims. (Cl. 193—35)

My invention relates to improvements in rails for use in industrial heat treating furnaces, such as carburizing furnaces or the like, through which the loaded work supports, such as trays, boxes or the like, are moved in tandem while supported on rollers mounted for rotation in rails.

Rails of this type are usually heavy, massive castings, and each installation and replacement involves the expenditure of considerable time and expense. The rails are subjected to the load bearing and travelling stresses as well as the heat conditions which prevail within the furnace, and thus have a relatively short effective life. Most of the wear is taken up by the bearings, in which the roller journals rotate, and if any one bearing in a rail becomes worn or cracked, the entire rail is affected and must be replaced. This, as above stated, is expensive, and it is the object of the present invention to provide a roller rail with separate, independent roller bearings.

Another object of my invention is the provision of a roller rail with replaceable and renewable bearings.

Another object of my invention is the provision of a roller bearing for roller rails which can be used in a number of different positions to increase the normal life of the rail construction.

My invention relates also to improvements in the roller rails themselves as well as in the roller bearings incorporated in the rails, and objects of my invention in addition to those pointed out hereinabove will in part be pointed out specifically, and in part will be apparent from the following description of several illustrative embodiments thereof.

In the drawing annexed hereto and made a part hereof,

Figure 1 is a plan view, partly in section along the broken line 1—1 of Fig. 2; of one form of roller rail constructed according to and embodying my invention;

Fig. 2 is a side elevational view thereof, also partly in section, along the broken line 2—2 of Fig. 1;

Fig. 3 is a transverse section on the line 3—3 of Fig. 2;

Fig. 4 is a transverse section on the line 4—4 of Fig. 2; and

Fig. 5 is a perspective view of the form of bearing shown in combination with the rail and roller in Figs. 1—4 inclusive.

Referring to the form of my invention illustrated in Figs. 1—5 inclusive, the rail section 10 is substantially channel or U-shaped in cross sec-

tion, having a preferably flat base 11, upon which the rail section is disposed within the furnace either on the furnace floor or other support therein, and vertical side walls 12, 12. Rail section 10 may be cast, rolled or otherwise formed, as desired, of heat and corrosion resisting metal alloy, preferably of nickel, chromium and iron composition. The bearing members 16 and the rollers 17 may also be formed of a similar, preferably higher grade, composition metal alloy.

In the upper edges of side walls 12, 12 of the rail 10, I form a number of pairs of transversely aligned, open notches 14, 14 of part polygonal shape, to receive the bearings 16. The pairs of notches 14 are preferably spaced at equidistant intervals along the length of the rail. I preferably form these notches 14, 14 as part of a regular polygon having an even number of sides, for example, notch 14 is shown having five sides, each of which is a side of an eight-sided polygon, i. e., an octagon. If desired, notch 14 might be formed with three sides, as part of a square, etc. The five sides of notch 14, which notch is open at the top, are of equal length, comprising vertical side walls 18, 18 angled walls 20, 20 and horizontal bottom wall 22 (see Fig. 2).

The bearing member 16 is shaped to fit and be received within notch 14, and its periphery 19 is shown angled to form an octagonal, or eight sided polygon, the sides of which conform to the outline of notch 14. Thus, as shown in Fig. 2, when bearing member 16 is placed within notch 14, the angled faces of the bearing member conform to the sides of the notch, which is so formed that the center of the bearing or trunnion is below the upper edge of the track. Any of the sides of the bearing member may be used as the bottom side.

Bearing member 16 is provided with enlarged end portions 24, 24, the peripheries of which end portions 24 correspond in outline to the periphery of bearing member 16, and said end portions 24 preferably have the same number of angled flat faces as does the bearing member 16. When the middle or recessed parts 15 of the bearing members 16 are inserted and received in notches 14, the enlarged end portions 24, 24 of the bearing members 16 are disposed one on each side of the side wall 12 of the rail 10 adjacent to the notch 14 and this arrangement serves to secure the bearing member 16 to the rail. Integral with and extending lengthwise of the rail walls 12 I provide a pair of shoulder portions 26, 26 which are located respectively on the inside, and on the outside of the rail wall 12. The bottom faces of

the end portions 24 of bearing members 16 rest on top of these shoulder portions 26 as at 28, and distribute the load bearing stresses over the rail walls.

5 Bearing members 16 are provided with tapered central bores 30, to receive the correspondingly tapered trunnions 32, 32 which are formed integral with rollers 18, and in assembling the rail, the trunnions 32, 32 are fitted into the bores 30 10 of members 16 and both the bearing members for a single roller can be placed within the aligned notches 14.

Most of the wear on the rail as a whole is borne by that portion of the bearing which is directly 15 underneath the roller trunnions. Thus, referring to Fig. 2, most of the wear on bearing 16 occurs at region 50, underneath trunnion or pintle 32, and after extended use it is inevitable that the journal becomes affected, either worn, cracked, 20 warped, or otherwise rendered unusable. With my arrangement, I am enabled to remove the bearing members 16 from the rail notches, turn the bearing member 16 so that a new face is down and replace the bearing member so that 25 the adjacent angled face 52 of the bearing now rests on the bottom of notch 14, underneath pintle or journal 32. With an octagonal bearing, it is possible to use same in eight different positions, and the life of the bearing is multiplied correspondingly.

The advantages of my invention reside in the fact that the bearing can be replaced and renewed, in effect, without affecting the rail itself. The rail is usually the heaviest and most expensive part of the assembly, and since weight is a cost factor, it is an advantage that the life of the rail is increased because, with separate bearings, it takes no wear or stresses directly. The angled faces of the bearing member make it 40 possible to use the same bearing member in as many different positions as there are faces. In

Figures 1 to 5, I have shown an octagonal bearing which can be used in eight different positions.

In all the modifications of my invention, I form notches of such depth, that the trunnions or pintles of the rollers are below the upper edge of 5 the rail walls. This arrangement prevents the bearing members from becoming dislodged from the notches.

With my renewable and replaceable bearings, I am enabled to use a permanent rail body, since 10 the rail body itself is usually affected to but a slight degree by ordinary furnace conditions.

Having now described my invention, what I claim and desire to secure by Letters Patent is:

1. A roller rail comprising a rail body portion 15 having a floor portion and side walls, transversely aligned, open, part polygonal notches provided in said side walls, bearing members of similar polygonal formation adapted to be removably received within said notches, and means on and a 20 part of the side walls below said notches bearing against the underside of the bearing members to support said bearing members therewithin, and rollers mounted for rotation within said bearing members.

2. A roller rail comprising a rail body portion having a floor portion and side walls, transversely aligned, open, part polygonal notches provided in said side walls, bearing members of regular polygonal formation similar in size and shape 30 to the notch formation disposed within said notches of the side walls, platforms on the side walls beneath the notches extending out from the walls and extending the length thereof, enlargements on the ends of said bearing members 35 overlying the said side walls and resting on said platforms serving to removably secure said bearing members within said notches, and rollers mounted for rotation in said bearing members.

HENRY H. HARRIS.
